UNITED STATES PATENT OFFICE.

BENJAMIN W. DAVIS, OF EVANSTON, WYOMING; JAMES J. DAVIS ADMINISTRATOR OF
SAID BENJAMIN W. DAVIS, DECEASED.

FLAG-SUPPORT.

1,300,352.

Specification of Letters Patent. Patented Apr. 15, 1919.

Application filed August 17, 1918. Serial No. 250,350.

To all whom it may concern:

Be it known that I, BENJAMIN W. DAVIS, a citizen of the United States, residing in the city of Evanston and State of Wyoming, 5 have invented new and useful Improvements in Flag-Supports, of which the following is a specification, reference being had to the accompanying drawings.

This invention pertains to flag supports, 10 and has for its object the production of a simple bracket support for flags and flag staffs which may be readily attached to walls or other vertical surfaces, and which when so located, will hold the flag in a convenient and graceful position.

A further object is to produce such device in a form which may be readily and quickly attached to or taken from a wall or similar place;

20 A further object is to produce such device in a simple, cheap and efficient form.

With these objects in view, attention is called to the accompanying drawings, wherein

25 Figure 1 is a perspective view of a flag staff and flag supported in position on a wall by means of this invention;

Fig. 2 is a front elevation;

Fig. 3, a side elevation;

30 Fig. 4, a plan view;

Fig. 5 shows a modified form of construction.

Referring more particularly to the drawings, my invention consists of the bracket 1 which may be made of glass, pewter, lead, 35 cast-iron, or similar material, or may be stamped from sheet metal. In this bracket is rigidly set the staple 2 projecting at right angles from the bracket 1, and with the 40 prongs thereof preferably disposed one above the other for better support. In one side of the bracket 1, and in a plane parallel to the plane of the staple 2, is cut the groove 3. This groove 3, however, while extending 45 parallel to the staple, is cut across the bracket 1 diagonally, or on an incline relative to the edges of the bracket for a purpose which will be hereinafter explained.

50 Transversely through the bracket 1 are pierced the two holes 4, same extending through the bracket 1 substantially at right

angles to the staple 2. A strand of wire or cord 5 is provided and inserted through the holes 4, so that the free ends stand out from the open side of the groove 3. 55

In the modified form shown in Fig. 5, the groove 3 instead of being at one side of the bracket is located on the front of the bracket, so that the staff 6 instead of being supported from the side would be supported 60 from the front of the bracket 1. In this case, the groove 3 would be cut slightly deeper at the lower end of the bracket than at the upper end, so as to give said groove 65 an outward inclination from the bottom upward.

In operation, the flag staff 6 to be supported is placed within the groove 3, after which the ends of the wire 5 are wrapped 70 taut around the staff as shown. This holds 75 the staff in firm contact against the bracket. The staple 2 is then pressed or driven into the wall with the flag staff in the desired position. It will be noted that the inclination given to the groove 3 across the bracket 1 enables the staff 6 to incline outwardly 80 from the wall surface at its upper portion in a natural and graceful position.

It will be noted that I have herein provided a simple and efficient bracket for supporting a flag staff or the like, which may be readily attached to a wall, or similar support, and as readily detached, and which may be used over and over.

While I have herein described a certain 85 specific manner and method of constructing the elements of my invention, it is understood that I may vary from the same in minor details, not departing from the spirit of my invention, so as best to construct a 90 practical device for the purpose intended, as defined in the appended claims.

What I claim to be new and patentable is:

1. A flag-staff support comprising a 95 bracket; a staple extended from one side thereof; a groove cut upon another side thereof; holes piercing the bracket transversely to the groove; and a flexible binder extended through the holes. 100

2. A flag-staff support comprising a supporting bracket formed with wall engaging

prongs on one side, a staff engaging groove on another side and transverse holes adjacent said groove; and a flexible binder extended through said holes.

5 3. A flag-staff support comprising a supporting bracket formed with an inclined, vertical groove upon one side; a staple set

in another side; cord securing holes pierced through the bracket; and a flexible binder extended through said holes.

BENJAMIN W. DAVIS.
